FLOUR SIFTER WITH RECIPROCATING AGITATOR

Frank R. Chester, Santa Monica, Calif.

Application May 23, 1945, Serial No. 595,400

7 Claims. (Cl. 209—282)

1

My present invention relates to a sifter particularly adapted for sifting flour for domestic purposes.

One of the principal objects of this invention is to provide a sifter of this class which may be easily gripped with one hand and which may be easily manipulated for sifting flour, and particularly one which may be mechanically operated by the same hand gripping the sifter.

Another important object of this invention is to provide a sifter of this class in which the perforations in the sifting receptacle are adapted normally to be closed or covered when the sifter is not in use, as when it is placed on a table, thereby preventing flour from falling or passing through the perforations when not desired.

An important object also of this invention is to provide simple means in connection with the sifter for supporting it in an upright position on a table when the sifter is not being used.

A further important object of this invention is to provide novel and simple means in connection with the sifter manipulating handle for mechanically and easily operating the agitating means thereof.

Still another important object of this invention is to provide a sifter of this class which may be principally formed of sheet metal stampings and formed wire parts.

A still further important object of this invention is to provide a sifter of this class in which is provided a baffle or retarding element for positively preventing the flour, or other material to be sifted, from being carried continuously undisturbed by the agitator or other moving element.

Further objects will be apparent from the following description and the drawings, which are intended for the purpose of illustration, and in which:

Fig. 1 is a longitudinal sectional view of my sifter in one form, showing the same resting upon a flat surface, the section being taken through 1—1 of Fig. 2;

Fig. 2 is a top view thereof, taken at 2—2 of Fig. 1, showing portions broken away to facilitate the illustration;

Fig. 3 is an enlarged transverse sectional view thereof, taken through 3—3 of Fig. 1;

Fig. 4 is an enlarged fragmentary sectional view thereof, taken through 4—4 of Fig. 1;

Fig. 5 is an enlarged sectional view thereof, taken through 5—5 of Fig. 1;

Fig. 6 is a fragmentary view of a portion of the handle and receptacle with the agitator operating member in a slightly modified form of construction; and

Fig. 7 is a fragmentary sectional elevation, similar to the container portion of Fig. 1, of a slightly modified construction of my sifter.

My sifter, as shown in the drawings, comprises

2

essentially a receptacle or bowl 1 and a handle 2 extending from one side of the former. As shown, the upper portion of the receptacle is round or cylindrical, and is provided with a hemispherical bottom 1a. These comprise the whole or only container or bowl of my sifter. Within the hemispherical bottom portion of the receptacle or bowl is an agitator 3 which is also partially spherically shaped, that is, it consists of a segment of a sphere, and is positioned substantially in engagement with the inner surface of the bottom. This agitator is pivotally mounted on an axis which passes through the spherical axis of the correspondingly shaped bottom of the receptacle. The pivotal mounting consists of a rod 4 from which the agitator depends and to which the upper portions thereof are secured. The rod 4 extends diametrically across the receptacle, through the outer portion and inwardly through the inner side of such receptacle, and also through the hollow portion of the handle 2. The rear end of the rod 4 extends through and is pivotally mounted in the rear end of the handle.

The bottom of the receptacle 1 is provided with perforations 1b which, in this instance, are arranged in rows, the axis of the pivoting rod serving as the center from which said rows emanate. The agitator is slotted to provide agitating elements 3a which also emanate from the axis of the pivoting rod and, when the agitator is in normal position, the elements 3a cover the rows of perforations. The agitating elements 3a are adapted to agitate and move the flour over the perforated bottom of the receptacle.

An agitator operating lever 5 of U-shaped cross-section is arranged at the underside of the handle. The forward end of the handle is pivotally mounted on a transverse axis near the forward end of the handle 2, the lever 5 being pivotally supported on a pin 6 which is supported at its ends in the opposite side walls 2a of the handle 2, which is of inverted U-shaped cross-section. The rear end of the lever 5 has an upwardly turned arm or web 5a, through the upper end of which extends the throw element 4a of a crank portion 4b located near the rear end of the rod 4, as shown best in Figs. 1 and 5. The upper end of the arm or web 5a has a short transverse slot 5b to permit lateral movement of the throw element 4a of the crank portion. As the lever 5 is oscillated about its pivot, the free end thereof moves the crank portion and rocks the rod about its axis.

Around the pivot pin 6 is a spring 7 which engages both interior portions of the handle 2 and lever 5 so as normally to force the free end of the lever 5 in extended position, substantially as shown in Fig. 1. This spring may be arranged to force the agitator to one extreme position. The movement of the free end of the lever may be lim-

ited by the bottom portion 2^b of the rear end of the handle 2.

When the handle 2 is gripped with one hand, the fingers of the same hand may draw the lever 5 upwardly, into the hollow portion of the handle 2, between the side walls 2^a, against the action of the spring 7, thereby causing the agitator to move in a direction opposite to that caused by the force of the spring 7.

As shown in Fig. 1, the sifter, when not in use, may be placed on a table or other surface. A pair of projections 1^c are provided at the lower side of the spherically shaped bottom so as stably to support the sifter on such surface. When the receptacle of the sifter is so supported, the rear end of the handle 2 may provide the third point of support, as indicated by 2^b.

The perforations 1^b and the agitating elements 3^a are so arranged that when the sifter is not in use, the spring 7 forces the agitator 3 to such a position that the agitating elements 3^a thereof cover the perforations 1^b so as to prevent the flour or other product from passing through the perforations. Such normal or perforation covering position is shown best in Figs. 2 and 3.

In Fig. 6 I have shown a slightly modified form for the mounting of the lever 5. In this instance, the forward end of the handle, designated 11, is rigidly secured to the opposite side walls 2^a of the handle 2, such as by rivets 12, or by welding. The intermediate portion of the lever 11 has a flat cross-section 11^a which permits ready distortion of such lever or arm and permits the rear end thereof to be readily oscillated for periodically rocking the rod 4 through the crank portion 4^b. In this manner, the aforementioned specific mounting of the lever 5 and the spring 7 may be eliminated.

In the modified construction, shown in Fig. 7, I have provided a baffle or retarding element 21 which extends across the receptacle 1 substantially between the pivoted sides of the agitator 3, to disturb the flour, or other product carried by the moving or oscillating agitator, and thereby facilitate its passage through the perforations.

The baffle 21 is shown as semi-circularly shaped and is secured, as by welding, to the wall of the receptacle 1, the ends being preferably secured to opposite sides of the pivotal axis of the agitator 3 or the axis of the rod 4.

The baffle 21 may be employed when desiring closer spacing of the agitator elements 3^a and the rows of perforations 1^b.

I wish it to be understood that I do not desire to be limited to the exact details of construction shown and described, for obvious modifications will occur to a person skilled in the art.

I claim:

1. A sifter comprising a substantially tubular body terminating at its lower extremity in a hemispherical bowl-like portion, a hollow handle open on the lower surface thereof extending laterally from said body, a rod journalled in said bowl-like portion and extending into said handle and also journalled in the outer extremity thereof, a crank portion on said rod adjacent the outer extremity thereof, a partially spherical agitator complementary to the interior of said bowl-like portion and secured to said rod for oscillation therewith, said agitator being slotted to provide a plurality of spaced agitating surfaces, a portion of the surface of said bowl-like portion being provided with a plurality of spaced rows of perforations staggered with respect to the slots in said agitator and whereby the agitating surfaces normally cover

said rows of perforations, a lever mounted at its forward end within said handle adjacent said bowl-like portion, said lever extending backwardly from its mounting and being operatively connected at the rear end thereof to said crank portion for oscillating said agitator when the lever is moved relative to said handle through the opening therein, whereby said agitating surfaces will alternately uncover and cover said rows of perforations, and means for returning said agitator to normal position.

2. A sifter comprising a substantially tubular body terminating at its lower extremity in a hemispherical bowl-like portion, a hollow handle open on the lower surface thereof extending laterally from said body, a rod journalled in said bowl-like portion and extending into said handle and also journalled in the outer extremity thereof, a crank portion on said rod adjacent the outer extremity thereof, a partially spherical agitator complementary to the interior of said bowl-like portion and secured to said rod for oscillation therewith, said agitator being slotted to provide a plurality of spaced agitating surfaces, a portion of the surface of said bowl-like portion being provided with a plurality of spaced rows of perforations staggered with respect to the slots in said agitator whereby the agitating surfaces normally cover said rows of perforations, a lever pivotally mounted at its forward end within said handle adjacent said bowl-like portion, said lever extending backwardly from its pivotal mounting and being operatively connected at the rear end thereof to said crank portion for oscillating said agitator when the lever is moved relative to said handle through the opening therein, whereby said agitating surfaces will alternately uncover and cover said rows of perforations, and spring means for returning said agitator to normal position.

3. A sifter comprising a substantially tubular body terminating at its lower extremity in a hemispherical bowl-like portion, a hollow handle open on the lower surface thereof extending laterally from said body, a rod journalled in said bowl-like portion and extending into said handle and also journalled in the outer extremity thereof, a crank portion on said rod adjacent the outer extremity thereof, a partially spherical agitator complementary to the interior of said bowl-like portion and secured to said rod for oscillation therewith, said agitator being slotted to provide a plurality of spaced agitating surfaces, a portion of the surface of said bowl-like portion being provided with a plurality of spaced rows of perforations staggered with respect to the slots in said agitator whereby the agitating surfaces normally cover said rows of perforations, a resilient lever rigidly secured at its forward end within said handle adjacent said bowl-like portion, said lever extending backwardly and being operatively connected at the rear end thereof to said crank portion for oscillating said agitator when the extremity of said lever is moved relative to said handle through the opening therein, whereby said agitating surfaces will alternately uncover and cover said rows of perforations, the resiliency of said lever serving to return said agitator to normal position.

4. A sifter as defined in claim 2 provided with a pair of projections on the bowl-like portion and a projection on the outer extremity of the handle disposed in substantially the same plane as said first mentioned projections whereby the sifter may be supported in upright position upon a substantially flat surface.

5. A sifter as defined in claim 3 provided with a pair of projections on the bowl-like portion and a projection on the outer extremity of the handle disposed in substantially the same plane as said first mentioned projections whereby the sifter may be supported in upright position upon a substantially flat surface.

6. A sifter comprising a body terminating at its lower extremity in a bowl-like portion provided with a plurality of apertures, a hollow handle open on the lower surface thereof extending laterally from said body, a rod journalled in said bowl-like portion and extending into said handle and also journalled in the outer extremity thereof, a crank portion on said rod adjacent the outer extremity thereof, an agitator complementary to the interior of said bowl-like portion carried by said rod for oscillation therewith, a lever mounted at its forward end within said handle adjacent said bowl-like portion, said lever extending backwardly from its mounting and being operatively connected at the rear end thereof to said crank portion for oscillating said agitator when the lever is moved relative to said handle through the opening thereof, means for returning said lever and agitator to normal position, and a supporting means for said sifter comprising spaced angularly related surface engaging portions on said handle and bowl-like portion to provide a three point support whereby said sifter may be supported in upright position on a substantially flat surface.

7. A sifter comprising a body terminating at its lower extremity in a bowl-like portion provided with a plurality of apertures, a hollow handle open on the lower surface thereof extending laterally from said body, a rod journalled in said bowl-like portion and extending into said

handle and also journalled in the outer extremity thereof, a crank portion on said rod adjacent the outer extremity thereof, an agitator complementary to the interior of said bowl-like portion carried by said rod for oscillation therewith, a resilient lever rigidly secured at its forward end within said handle adjacent said bowl-like portion, said lever extending backwardly and being operatively connected at the rear end thereof to said crank portion for oscillating said agitator when the extremity of said lever is moved relative to said handle through the opening therein, the resiliency of said lever serving to return said agitator to normal position, and a supporting means for said sifter comprising spaced angularly related surface engaging portions on said handle and bowl-like portion to provide a three point support whereby said sifter may be supported in upright position on a substantially flat surface.
